(57) **CLAIM**

I claim the ornamental design for a bar, as shown and described.

DESCRIPTION

FIG. 1 is a front elevation view of the bar of the present invention.

FIG. 2 is a rear elevation view of the bar of the present invention.

FIG. 3 is a right elevation view of the bar of the present invention.

FIG. 4 is a left elevation view of the bar of the present invention.

FIG. 5 is a top plan view of the bar of the present invention.

FIG. 6 is a bottom plan view of the bar of the present invention; and,

FIG. 7 is a perspective view thereof.

The broken lines are for environmental purposes only and form no part of the claimed design.
